UNITED STATES PATENT OFFICE

WALTER G. MADISON, OF AMES, IOWA

ADJUSTABLE RADIATOR BRACKET

Application filed July 13, 1931. Serial No. 550,544.

5 The object of this invention is to provide an improved construction for a bracket or hanger for supporting radiators of a heating system.

10 5 A further object of the invention is to provide an improved wall bracket for radiators, the bracket having certain elements capable of adjustment for securing the desired positioning of the radiator.

15 10 Still another object of the invention is to provide an improved radiator bracket which is of rugged yet simple and inexpensive construction and which lends itself to ease and quickness of installation.

20 15 With these and other objects in view my invention consists in the construction, arrangement and combination of the various parts of my device, whereby the objects contemplated are attained, as hereinafter more fully set forth, pointed out in my claims, and illustrated in the accompanying drawing, in which:—

25 Figure 1 is a perspective view of my improved radiator bracket.

30 25 Figure 2 is a plan view illustrating a radiator supported from a wall or the like by means of two of the brackets constituting my invention.

35 30 Figure 3 is an enlarged vertical section on the line 3—3 of Figure 2, the dotted lines indicating the tilted position which may be assumed by the bracket in placing it on a lag screw carried by the wall.

40 35 Figure 4 is a detail section of a portion of the supporting means, substantially on the line 4—4 of Figure 3.

45 The bracket or hanger includes the vertical body 10 having at its upper end a forwardly projecting lug 12 and at its lower end a forwardly projecting lug 14. The lugs 12 and 14 are V-shaped or pointed at their outer extremities and are adapted to fit between adjacent sections 16 of a radiator assembly to be supported by the bracket.

Preferably the upper lug 12 is connected

50 at its sides to the side margins of the body plate 10 by means of webs or flanges 18 and the lower lug 14 is connected to the body plate by means of a web or fillet 20 for strengthening purposes.

55 The body plate 10 is formed near its upper end with an enlarged opening 22 extending therethrough and adapted to accommodate a lag screw or the like 24 which may be seated in a wall such as 26 from which a radiator is to be supported. The lag screw 24 preferably is equipped with a special form of washer 28 which has a flat face for engaging the face of the wall 26 and which serves to space the head of the lag screw a suitable 60 distance from the wall. The washer 28 preferably is formed at its upper rear side with a notched out portion 28' which serves to expose a portion of the stem of the lag screw and to permit the body plate 10 of the bracket 65 immediately above its opening 22 to engage directly with the screw as illustrated most clearly in Figure 3. By this means the bracket is adapted to be supported on the wall.

70 70 A hanger bolt 30 is provided and is extended loosely through the forward portion of the upper lug 12 of the bracket. The bolt 30 is threaded at its upper end and provided with a nut 32. The bolt 30 is bent or curved between its ends so that its lower portion is directed forwardly in substantially a horizontal plane and is adapted to project between two radiator sections 16.

75 80 A hanger plate 34 is provided and is formed in its lower part with an opening 36, preferably a downwardly directed notch. The notch 36 preferably is rectangular in section and is adapted to fit snugly the squared portion 30' adjacent the head of the hanger 85 bolt 30 as shown particularly in Figure 4. The hanger plate 34 extends upwardly from the horizontal part of the curved hanger bolt 30 and engages two of the radiator sections 16 90 in supporting position. The plate 34 is ar-

ranged to extend transversely of the space between two adjacent sections 16 and enters the slots 38 of both sections. The slots 38 are such as are commonly formed between the columns of radiator sections and the top edge of the plate 34 engages the two adjacent sections at the upper ends of their slots and thereby supports the radiator.

There is preferably provided a brace member or stabilizing member and this may be in the form of a screw or bolt 40 having a threaded connection with the lower end of the body plate 10 of the bracket. The stabilizing bolt 40 carries a bar washer 42 which is adapted to be extended transversely of the space between two radiator sections 16 and to engage in the slots 38 thereof. After the radiator has been mounted on the bracket and put in place on its support the stabilizing bolt 40 may be tightened up to hold the radiator close to the lower end of the bracket and in engagement with the pointed end of the lower lug 14 to prevent lateral or outward swinging movement of the radiator and to keep it plumb regardless of irregularities in the wall. This tightening operation may be accomplished by inserting a screw driver between the two radiator sections from the front or outer side as will be readily understood.

In use one or more of the brackets are used for each radiator unit as indicated in Figure 2.

The lag screws 24 are first seated in the wall at the desired locations. The brackets are attached to the radiator by placing the forwardly projecting lugs 12 and 14 in engagement with two of the sections and with their pointed portions extending therebetween and with the bolts 30 and 40 also extending between the sections. The hanger plates 34 are caused to engage the ends of the curved bolts 30 and the brackets are adjusted to such positions that the upper edges of the hanger plates contact with the upper ends of the slots 38 of the two sections and then the nuts 32 are tightened. The bar washers of the stabilizing bolts 40 are also placed in transverse positions and the bolts are tightened in their seats in the bracket.

When the brackets have thus been mounted on the radiator and both bolts made tight, the radiator is ready to be installed and this is accomplished by causing the openings 22 of the body plates to engage over the projecting lag screws and over the special washers 28 thereon. This may be accomplished by a slight tilting movement as indicated by dotted lines in Figure 3, after which the base plates 10 of the brackets assume positions in engagement with the face of the wall and the radiator is thus supported in slightly spaced relation to the wall.

The elongated openings 22 in the body plates of the brackets permit some adjust-

ment to bring the radiator to the desired location.

It is obvious that I have provided a rugged, durable and efficient type of radiator hanger or bracket and that it is a comparatively easy matter to make the installation by using these brackets.

Some changes may be made in the construction and arrangement of the parts of my device, without departing from the real spirit and purpose of my invention, and it is my intention to cover by my claims, any modified forms of structure or use of mechanical equivalents, which may be reasonably included within their scope.

I claim as my invention:—

1. A hanger for radiators comprising a body plate formed with forwardly projecting lugs adapted to engage between adjacent radiator sections, means for supporting said plate on a wall, a hanger bolt carried by one of said lugs, said bolt adapted to extend between the radiator sections, and a hanger plate carried by said bolt for engaging beneath parts of both sections.

2. A hanger for radiators comprising a body plate formed with forwardly projecting lugs adapted to engage adjacent radiator sections, means for supporting said plate on a wall, a hanger bolt carried by one of said lugs, said bolt adapted to extend between the radiator sections, and a hanger plate carried by said bolt for engaging beneath parts of both sections, said bolt being provided with a turnable nut engaging above the lug which carries the bolt to permit adjustment of said hanger bolt from a position above its supporting lug.

3. A hanger for radiators comprising a body plate formed with projecting lugs adapted to engage a radiator, means for securing the radiator to the hanger in contact with said lugs, an opening being formed through said body plate, a lag screw or the like, adapted to be secured to a wall, and to extend through the opening in said body plate, and a special washer on said lag screw of greater thickness than the thickness of said body plate, said washer being notched at its upper inner portion adjacent the wall to permit a portion of the body plate to enter said notched portion and to be held thereby in contact with the wall.

4. A hanger for radiators comprising a body plate formed with forwardly projecting lugs, said lugs being pointed at their ends for engaging between adjacent radiator sections, means for supporting said plate on a wall, a hanger bolt carried by one of said lugs, said bolt being bent between its ends substantially at right angles and adapted to extend between the radiator sections, and a hanger plate carried by said bolt for engaging beneath parts of both sections.

5. In a radiator hanger, a body plate,

means for supporting said plate on a wall, a lug on said plate projecting forwardly therefrom, a hanger bolt extending through said lug and threaded at its upper end to receive a nut above said lug, said bolt being bent substantially at right angles between its ends to provide a substantially horizontal portion adapted to extend between parts of a radiator structure, and a hanger plate apertured to engage the horizontal portion of said bolt, said hanger plate extending above said horizontal portion into supporting engagement with parts of the radiator structure.

Des Moines, Iowa, June 29, 1931.
